US00D937107S

(12) **United States Design Patent** (10) **Patent No.:** **US D937,107 S**
(45) **Date of Patent:** **** Nov. 30, 2021**

(54) **TARGET BOARD**

(71) Applicant: **AUTEL INTELLIGENT TECHNOLOGY CORP., LTD.**,
Guangdong (CN)

(72) Inventor: **Yongshuai Wang**, Guangdong (CN)

(73) Assignee: **AUTEL INTELLIGENT TECHNOLOGY CORP., LTD.**,
Shenzhen (CN)

(**) Term: **15 Years**

(21) Appl. No.: **29/725,738**

(22) Filed: **Feb. 26, 2020**

(30) **Foreign Application Priority Data**

Aug. 26, 2019 (CN) 201930465058.7
(51) **LOC (13) Cl.** **10-04**
(52) **U.S. Cl.** ..... **USPC** **D10/65**; D8/349

Primary Examiner — Katherine Glennon

(57) **CLAIM**

The ornamental design for a target board, as shown and described.

DESCRIPTION

FIG. 1 is a front elevational view of a target board showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

1 Claim, 6 Drawing Sheets
